ROPE MEASURING APPARATUS.
APPLICATION FILED JULY 10, 1913.

Patented Dec. 8, 1914.

2 SHEETS-SHEET 2.

UNITED STATES PATENT OFFICE.

THOMAS C. BOUNDS, OF WAHALAK, MISSISSIPPI, ASSIGNOR OF ONE-HALF TO JAMES R. BOUNDS, OF WAHALAK, MISSISSIPPI.

ROPE-MEASURING APPARATUS.

1,120,126.

Specification of Letters Patent.

Patented Dec. 8, 1914.

Application filed July 10, 1913. Serial No. 778,321.

To all whom it may concern:

Be it known that I, THOMAS C. BOUNDS, citizen of the United States, residing at Wahalak, in the county of Kemper and State 5 of Mississippi, have invented certain new and useful Improvements in Rope-Measuring Apparatus, of which the following is a specification.

This invention relates to means for measuring rope or similar merchandise and has 10 for its object the provision of a simple and inexpensive mechanism by which a store-keeper may rapidly and accurately measure off a length of rope desired by a customer 15 without the necessity of applying a scale directly to the rope.

The invention also has for its object the provision of means whereby a coil of rope may be placed in position and supported 20 within the apparatus whether the rope is supplied by the manufacturer with or without a core piece and the invention also has for its object the provision of means whereby the end of the rope may be held against 25 withdrawal and in position to be easily grasped by the salesman when supplying a second customer.

A further object of the invention is to provide means whereby the registering mechanism may be effectually held in operative position at all times, and finally the object of the invention is to improve generally the construction and arrangement of the parts 30 of a rope measuring apparatus to the end that the durability and efficiency of the same 35 may be increased.

The invention is illustrated in the accompanying drawings and will be hereinafter first fully described in detail and the novel 40 features will then subsequently be particularly pointed out in the claim following the description.

In the drawings: Figure 1 is a perspective view of the complete apparatus, showing the 45 same in the position in which it will ordinarily be placed for use; Fig. 2 is a vertical transverse section; Fig. 3 is a horizontal section on the line 3-3 of Fig. 2. Fig. 4 is a detail view of a slight modification.

50 In carrying out my invention I employ a supporting frame which may be of any convenient or preferred construction and is illustrated as comprising a pair of spaced standards or back plates 1 which are adapted to be secured to the wall of a store-room

or any other fixed support and are maintained in the proper spaced relation by a cross bar 2. From the said standards project supporting arms 3 which are connected to the standards by braces 4 whereby breaking of the arms, under the weight imposed upon them, will be prevented. In the upper edges of the said arms, near the outer ends thereof, are notches 5 adapted to receive trunnions or pins 6 at the ends of a core 65 block or roller 7. When a coil of rope is supplied upon a spool or core piece by the manufacturer, the roller or core block 7 will be inserted through the said core piece and the pins or trunnions 6 then engaged in 70 the notches 5 so that the coil of rope will be supported between the arms 3. If, however, the maker of the rope furnishes it in a loose coil without a core piece, I employ the supplemental core member 8 which is in the 75 form of a tube having an inner diameter which will permit it to fit easily upon the core block 7 and at the same time be held against movement independently of the core block. While I have illustrated these members 7 and 8 as angular in end view or cross section, it will be understood, of course, that the particular shape is entirely immaterial.

To the lower ends of the standards 1 I secure a back plate 9 from which extends a 85 shelf 10 and upon the said shelf I erect a cross plate 11 in advance of the back plate 9 and also provide a small standard or other support 12. This support or standard 12 is in advance of the cross plate 11 and I have 90 illustrated a similar support 13 as provided immediately adjacent the said cross plate 11, but it will be understood of course that this inner support 13 may be dispensed with. A dial or indicator plate 14 is secured to the 95 front face of the support 12 and upon the front face of this indicator plate or dial are a series of graduations 15 by which the length of rope drawn from the coil may be indicated.

An indicator shaft 16 is journaled near its front end in the front standard or support 12 and a pointer or indicator 17 is fixed upon the extremity of the said shaft so as to play in front of the dial 14. The inner 105 or rear end of this shaft plays in a vertical slot 18 formed in the inner support 13 and a spring 19 is secured to the shelf 10 and engaged over the said shaft so that it tends to draw the shaft to the bottom of the said 110

slot, thereby holding a worm wheel 20, rigid upon the said shaft, in constant mesh with the worm shaft 21 which extends between the supports 12 and 13 below the said worm wheel and has one end journaled in a side support 22, erected upon the shelf 10 at one side of the same, and is journaled at its opposite end in spaced standards or plates 23 which form a guide chamber for the free end of the rope 24. A grooved pulley 25 is fixed upon the shaft 21 between these plates or standards 23 and the rope passes over the said pulley, as clearly shown in Fig. 2 and as will be readily understood.

15 From the rotary support, furnished by the core members 7 and 8, or the core member 7, is inserted through the center of the coil of rope and is then engaged in the notches 5 in the supporting arms 3 so that the rope will be supported in an accessible position, while at the same time it will not be using floor space. The free end of the rope is carried in rear of and then under the guide roller 26 and is then inserted between the side plates 23 and the rollers 25 and 28, the roller 28 being held raised by manipulating the handle 32, as will be readily understood.

20 When the end of the rope has been fed beyond the front edges of the side plates 23, the lever 32 is released and the end of the rope will then be clamped between the rollers 25 and 28. When a sale is to be made, the free end of the rope is grasped and the

25 rope is then simply drawn out until the indicator 17 is moved to that numeral upon the dial 14 which will indicate that the desired length of rope has been drawn out. Of course, when the first sale is made, the indicator will be moved to numerals indicating exactly the length of rope drawn out, that is to say, if ten feet of rope are wanted, and no previous sales have been made, the indicator will be at zero and when it reaches

30 10, the salesman will stop drawing rope from the apparatus and will cut-off the length drawn out. If the next sale is to be of fifteen feet of rope, the salesman will first note the position of the indicator, which will then be at 10 and by then adding the desired quantity (15) to the numeral at the end of the indicator will know that he should continue drawing rope until the indicator reaches the number 25. As the

35 rope is drawn from the device its frictional engagement, which is enhanced and positively maintained by the action of the plunger 27, will cause the roller 25 and the shaft 21 upon which it is fixed, to rotate and the rotation of the shaft 21 will, of course, actuate the worm wheel 20 and the indicator shaft 16 so that the indicator will be positively moved in front of the dial 14 as long as rope

40 is being drawn from the device.

45 It is thought that the operation and advantages of the apparatus will be readily understood from the foregoing description, taken in connection with the accompanying drawings. Rope, as is well known, is supplied by rope makers in large coils which are generally mounted upon a reel and when a sale is to be made the storekeeper or salesman is required to draw off a length of the

50 rope from the coil and can only determine

when the desired quantity has been drawn from the reel by measuring the same with a tape measure or other similar scale. This operation is slow and laborious and will not be necessary where my improved apparatus is installed.

55 In using my device, the core members and 8, or the core member 7, is inserted through the center of the coil of rope and is then engaged in the notches 5 in the supporting arms 3 so that the rope will be supported in an accessible position, while at the same time it will not be using floor space. The free end of the rope is carried in rear of and then under the guide roller 26 and is then inserted between the side plates 23 and the rollers 25 and 28, the roller 28 being held raised by manipulating the handle 32, as will be readily understood.

60 When the end of the rope has been fed beyond the front edges of the side plates 23, the lever 32 is released and the end of the rope will then be clamped between the rollers 25 and 28. When a sale is to be made, the free end of the rope is grasped and the

65 rope is then simply drawn out until the indicator 17 is moved to that numeral upon the dial 14 which will indicate that the desired length of rope has been drawn out. Of course, when the first sale is made, the indicator will be moved to numerals indicating exactly the length of rope drawn out, that is to say, if ten feet of rope are wanted, and no previous sales have been made, the indicator will be at zero and when it reaches

70 10, the salesman will stop drawing rope from the apparatus and will cut-off the length drawn out. If the next sale is to be of fifteen feet of rope, the salesman will first note the position of the indicator, which will then be at 10 and by then adding the desired quantity (15) to the numeral at the end of the indicator will know that he should continue drawing rope until the indicator reaches the number 25. As the

75 rope is drawn from the device its frictional engagement, which is enhanced and positively maintained by the action of the plunger 27, will cause the roller 25 and the shaft 21 upon which it is fixed, to rotate and the rotation of the shaft 21 will, of course, actuate the worm wheel 20 and the indicator shaft 16 so that the indicator will be positively moved in front of the dial 14 as long as rope

80 is being drawn from the device.

85 In Fig. 4 I have shown an arrangement which will permit the pointer to be returned to zero after each sale, if desired. In this form of the device, the pointer 40 is loosely mounted on the indicator shaft which is

90 provided with a rib or flange 41 between the pointer and the dial. A spring 42 is coiled around the end of the shaft and bears upon the pointer so as to hold it normally in frictional engagement with the rib 41

whereby, when the shaft rotates, the pointer will move over the dial but it may be moved manually about the shaft as a center so as to be returned to the zero position. The 5 spring is retained on the shaft and adjusted to proper tension by a nut 43 threaded on the end of the shaft, as shown and as will be readily understood.

It will be readily noted that my device is 10 exceedingly simple in the construction and arrangement of its parts and that all the moving parts are protected against chance blows which might injure them to such an extent as to render the apparatus inoperative. The rope may be easily placed in 15 position to be reached and drawn from the apparatus and will be supported in such a manner that it will need no attention, except to supply customers and to replenish 20 the stock when the rope carried by the core has been exhausted. While I have illustrated the counting mechanism as disposed below the supporting members, it will be understood, of course, that the device might 25 be inverted without involving any substantial departure from the invention and other minor changes may be made without depart-

ing from the scope of the invention as the same is defined in the following claim.

Having thus described the invention, what 30 is claimed as new is:

An apparatus for the purpose set forth comprising a frame, a core rotatably mounted thereon, a housing on the frame below the core, a worm-shaft mounted on the 35 frame and having one end extending into said housing, a plunger mounted in said housing and bearing upon the rope passing from the core to hold the same in frictional engagement with the worm-shaft, means for 40 releasing the plunger, an indicator shaft mounted in the frame above the worm-shaft, a worm-wheel on the indicator shaft meshing with the worm-shaft, and a spring secured on the frame and connected to the 45 indicator shaft to hold the worm-wheel down in mesh with the worm-shaft.

In testimony whereof I affix my signature in presence of two witnesses.
